UNITED STATES PATENT OFFICE.

WILLIAM H. GREENLEAF, OF HARTFORD, CONNECTICUT.

DESIGN FOR A PUZZLE-BOX.

45,709.

Specification for Design.

Patented May 5, 1914.

Application filed February 6, 1914. Serial No. 817,076. Term of patent 3½ years.

To all whom it may concern:

Be it known that I, WILLIAM H. GREENLEAF, a citizen of the United States, and a resident of Hartford, in the county of Hartford, State of Connecticut, have invented a new, original, and ornamental Design for a Puzzle-Box, of which the following is a specification, reference being had to the accompanying drawing, forming part hereof.

Figure 1 is a plan view of a puzzle box

illustrating my new design. Fig. 2 is a sectional view on the line 2—2 of Fig. 1.

I claim:

The ornamental design for a puzzle box as shown.

WILLIAM H. GREENLEAF.

Witnesses:

A. E. O'BRIEN,
H. E. HART.
